UNITED STATES PATENT OFFICE

2,461,606

WORK SUPPORTING MEANS FOR HEAT
TREATING FURNACES

Harold F. Jackson, Springfield, Ohio, assignor to
The Ohio Steel Foundry Company, Lima, Ohio,
a corporation of Ohio

Application August 2, 1946, Serial No. 688,129

8 Claims. (Cl. 263—47)

1

This invention relates to means for supporting work in its passage through carburizing or other heat treating furnaces, and particularly to such means of the flexible tray pipe.

In the use of work supporting means of this character, it is frequently desirable to support the work in elevated position within the furnace a distance above the bottom or guiding rails, and also to support the work in a manner to permit flexing of the supporting means so as to permit warpage or distortion thereof, due to heat action or uneven guiding rails, without danger of breakage.

The primary object of the invention is the provision of a work supporting means of the character described which will answer the above requirements in a novel, efficient and simple manner.

A further object of the invention is the provision of a work support of this character that is capable of having its parts easily assembled or disassembled and to be compactly packed for shipment or storage when in knockdown condition.

Further objects and advantages of the invention will be apparent from the following detailed description and from the accompanying drawings illustrating one embodiment of the invention, in which:

Fig. 1 is a top plan view of a work supporting means embodying the invention, with parts broken away; Fig. 2 is a side elevation thereof, with parts broken away and partially shown in dotted lines; Fig. 3 is an enlarged section on the line 3—3 in Fig. 1; Fig. 4 is an enlarged perspective view of one of the tray members; Figs. 5 and 6 are enlarged top and side views, respectively, of one of the bars on which the tray members are mounted; Figs. 7 and 8 are side and end views, respectively, of a supporting post for the superstructure by which the work is supported; Fig. 9 is an end elevation of the work support embodying the invention, and Figs. 10 and 11 are top and side views, respectively, of the post supporting link members of the base structure, with the associated tie-rod fragmentarily shown in connection with the former.

Referring to the drawings, 1 designates a base structure 2, a superstructure, and 3 supporting posts of a work supporting means embodying the invention.

The base structure 1 comprises two end runners 5, 5, and a center runner 6 loosely connected together in spaced relation at their ends by respective side bars 7, 7. Each bar 7 is disposed

freely between pairs of spaced piston lugs 8 on the respective ends of each runner 5 and 6 and is loosely connected to each pair of lugs by a respective rod 9. The rods 9 are mounted for free lateral movements both in the lugs 8 and bars 7, the apertures 10 receiving the rods in the lugs being vertically elongated.

A pair of links or bars 11 connect the rods 9 on each runner 5 to the rod 9 on the center runner, and these links are quite widely spaced with one adjacent to each side bar 7. The links 11 are loosely mounted on the rods between respective pairs of lugs 12 on the runners 5 and lugs 13 on the center runners, with the rods freely movable in apertures in the lugs. The inner ends of the adjacent links each have sidewise lapping relation between the respective lugs 13. Each rod 9 is provided with one or more ring welds 14 to limit its lengthwise movement in the lugs.

Each link 11 is provided in longitudinally spaced relation and preferably near each end thereof with a vertical aperture 15 for receiving the lower end studs 16 of a respective post 3, so that the post is supported in upright position by the link in substantially rigid relation thereto. These posts may be of any desired length to support the superstructure 2 in proper elevated position. Each post 3 is provided at its upper end with a shoulder 17 and a stud 18 projecting upward therefrom.

The superstructure 2 comprises, in the present instance, a pair of bars 20 spaced lengthwise of the runners and each in vertical register with the respective set of longitudinally aligned links 11 of the base structure and supported by the post 3 rising therefrom. The bars 20 rest on the supports or shoulders 17 of the post 3 and have apertures 21 through which the studs 18 project. The bars 20 are substantially coincident in length with the front and rear side bars 7 of the post structure.

A plurality of tray or grid sections 22, of elongated rectangular form, are mounted in adjacent side-by-side relation on and in connection with the bars 20 crosswise thereof, as best shown in Fig. 1. These tray sections are of sufficient number to substantially extend from end to end of the bars 20 and have their ends extending beyond the bars and preferably terminating substantially in vertical alignment with the side bars 7 of the base structure.

Each tray section 22 is provided over each bar 20 at the same half of each side edge with half round ears 24 and half round recesses 25 at the inner ends of the ears, with the recess bottoms

in the planes of the inner sides of the ears, as shown in Fig. 4. Each ear is provided with an aperture 26 concentric to the recess 25. In assembling the tray sections on the bars 20, the sections are alternately positioned so that the ears 24 will lap registering ears of the adjoining sections and the ears will project laterally into the associated recesses 25 with the apertures 26 of one in vertical register with the apertures 26 of the other.

The studs 18 on the upper ends of the posts 3 project through and above the apertures 21 in the bars 20 and into registering apertures 26 in certain of the tray sections, thus serving to loosely hold the sections in assembled relation on said bars. Certain of the apertures 26 are disposed intermediate the posts 3 and these receive lugs 27 projecting up from the bars 20. The tray sections 22 are duplicates and can, therefore, be made in the same mold, it being necessary in assembling to merely reverse the position of each section relative to a preceding section.

It is apparent that the various parts of both the base and superstructure 1 and 2 are loosely connected in a manner to permit relative flexing movement thereof so as to prevent breakage when warping or distorting of either or both structures take place by reason of any unevenness in the supporting rails traversed by the runners 5 and 6 or of heat conditions. All of the connecting joints of the various parts, with the exception of the connection of the parts 3 with the links 11, are left loose to permit such flexing action and to prevent the transfer of strain from one part to another when any warping or distortion takes place.

I wish it understood that my invention is not limited to any specific construction, arrangement or form of the parts, as it is capable of numerous modifications and changes without departing from the spirit of the claims.

Having thus described my invention, what I claim as new, and desire to secure by United States Letters Patent, is:

1. In a work supporting means of the class described, a flexible structure having transversely spaced bars, and a plurality of tray sections of oblong rectangular form mounted in side-by-side relation on said bars and capable of flexing movements relative to each other and to the bars.

2. In a work supporting means of the class described, a flexible structure having transversely spaced bars and a plurality of tray sections of oblong rectangular form in side-by-side relation on said bars, said sections having loose lost motion connection with each other and with said bars.

3. A combination as called for in claim 2 together with means forming an elevated support for said structure.

4. In a work supporting means of the class described, a structure comprising a plurality of transversely spaced bars and a plurality of tray sections mounted side-by-side on said bars substantially throughout their lengths, and means on the bars interengaging with at least some of

the sections to retain them in assembled relation on the bars.

5. In a work supporting means of the class described, a structure comprising a plurality of transversely spaced bars, and a plurality of tray sections mounted side-by-side on said bars substantially throughout their lengths, and supporting means for the bars having parts interengaging with at least some of the sections to retain them in assembled relation on the bars.

6. In a work supporting means of the class described, a flexible structure comprising transversely spaced bars, and a plurality of tray sections of oblong rectangular form mounted in side-by-side relation on said bars and capable of flexing movements relative to each other and to the bars, said sections being of duplicate form and having ears at their sides for lapping the ears of an adjoining section, said lapping ears having registering vertically disposed perforations therein, and stud means projecting above said bars and freely entering said apertures to retain the sections in assembled relation on the bars.

7. In a work supporting means of the class described, a base structure comprising a plurality of transversely spaced runners having upstanding lugs, a rod carried by each runner lengthwise thereof and loosely mounted in said lugs, front and rear side bars loosely connected to all of said rods to tie the several runners together, a pair of transversely spaced links disposed intermediate said side bars at each side of the center runner and loosely connected at their ends to the rods of the respective end and center runners, posts mounted on and rising from said links, and an elevated work supporting tray structure mounted on and supported by said posts.

8. In a work supporting means of the class described, a base structure comprising a plurality of transversely spaced runners having upstanding lugs, a rod carried by each runner lengthwise thereof and loosely mounted in said lugs, front and rear side bars loosely connected to all of said rods to tie the several runners together, a pair of transversely spaced links disposed intermediate said side bars at each side of the center runner and loosely connected at their ends to the rods of the respective end and center runners, posts mounted on and rising from said links, and an elevated work supporting tray structure mounted on and supported by said posts, said elevated structure having flexible characteristics and being loosely carried by said posts.

Certificate of Correction

Patent No. 2,461,606.

February 15, 1949.

HAROLD F. JACKSON

It is hereby certified that error appears in the printed specification of the above numbered patent requiring correction as follows:

Column 1, line 4, for the word "pipe" read *type*;
and that the said Letters Patent should be read with this correction therein that the same may conform to the record of the case in the Patent Office.

Signed and sealed this 14th day of June, A. D. 1949.
